VAPORIZER AND CONTROL PANEL

Frederick W. Glossbrenner, Indianapolis, Ind.

Application October 13, 1947, Serial No. 779,569

3 Claims. (Cl. 219—38)

1

The present invention relates to a vaporizer and control panel, and is particularly concerned with the provision of such an assembly primarily intended for use in connection with a vapor bath cabinet, or the like. The primary object of the invention is to provide a vaporizer and control panel assembly which shall be readily associable with, or removable from, a bath cabinet of more or less standard construction, to supply vapor to the cabinet, to control the supply of vapor, and to control the heating device ordinarily built into such a cabinet. Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a fragmental perspective view of one end of a cabinet of standard construction, the assembly of the present invention being associated therewith;

Fig. 2 is a horizontal section, showing the heating unit and tank of my vaporizer;

Fig. 3 is a vertical section, showing the internal construction of my vaporizer, and the manner of its association with the cabinet vapor header;

Fig. 4 is a plan view of my vaporizer, with the cover open; and

Fig. 5 is an end elevation, showing my control panel and a portion of the cabinet wall with which it is associated.

In the drawings, I have shown a part of a standard vapor bath cabinet, indicated generally by the reference numeral 10, and including an end wall 11. In accordance with standard practice, a distributing header 12 is built into the cabinet and it opens through said wall 11, as is clearly to be seen in Fig. 3. Usually on the internal surface of the wall 11, there is supported an infrared heating device, indicated by the reference numeral 13; and of course that device is provided with an energizing circuit which, as illustrated, terminates in a connector fitting 14 mounted upon the wall 11 and accessible from the outside of said wall.

According to the present invention, my vaporizer, indicated generally by the reference numeral 15, comprises a tank having a bottom wall 16, front and back walls 17 and 18, and end walls 19 and 20 upstanding from the bottom wall 16, and leaving the top of the tank substantially open.

2

Spanning the upper ends of the walls 17 and 18 are a pair of straps 21 and 22, each of which is deformed with a central threaded perforation 23.

The upper ends of the side and end walls of the tank may be turned inwardly, as at 24, to provide a flange upon which may be seated a gasket 25 of rubber or any other suitable sealing material, and a cover plate 26 may be removably supported upon said gasket. The cover plate 26 is formed, adjacent each end, with an opening 27, said openings being adapted to register with the openings

23 in the straps 21 and 22; and a screw 28, having a manipulating knob 29 at one end thereof is provided for each of said openings 27. The screws 28 will, of course, penetrate the openings 27 and thread into the openings 23 to clamp the cover plate in place when the vaporizer is in operation.

The cover plate is provided with an intermediate threaded opening in which may be received a screw carrying a knob 30, whereby the cover plate 26 may be manipulated. All the knobs 29 and 30 will preferably be formed of suitable material, such as molded plastic, having a substantial heat-insulating effect.

Ports 31 and 32 are formed in the wall 17 at vertically spaced points, and a sight glass 33, provided with end fittings 34 and 35, is mounted upon the tank with said fittings 34 and 35 in registry with the ports 31 and 32. Thereby, the liquid level in the tank may always be ascertained by inspection of the sight glass 33.

Near the upper end of the wall 18 is formed a port with which registers a short pipe section 36 rigidly fixed to said wall 18 and projecting therefrom. The pipe 36 is so proportioned and designed as to be telescopically insertible into the header 12. The tank 15 may be supported solely by the engagement of the pipe section 36 in the header 12; but I prefer to provide a bracket 37, of any suitable construction, fixed to the wall 11 and so related to the header 12 that, when the pipe section 36 is received in said header, the bracket will provide additional support for the tank 15.

The tank wall 20 is formed, near its lower end, with an opening 38 in which may be mounted an immersion type electric heater indicated generally by the reference numeral 39. Said heater will preferably be of the kind providing two or more heating elements 40 and 41 which will be suspended near the bottom of the tank and in the body of the liquid therein. A nut 42 and a nut 43, threaded onto the body of the unit 39, on opposite sides of the wall 20, act to clamp the unit 39 in position.

A control panel 44 is readily removably attached to the wall 11 by means of suitable brackets 45. An electrical connector fitting 46 of the male-knife blade type is mounted upon the panel 44 in the manner illustrated, whereby its blades are exposed, but sunken beneath the surface of the panel. The terminals of said fitting are connected, by suitable wiring, through a three-way switch 47 mounted upon said panel, to the energizing circuits of the unit 39, by means of a standard connector cord 48. Said terminals of the fitting 46 are further connected, through a parallel circuit, and through a switch 49 mounted on the panel 44, to a standard electrical connector cord 50 whose opposite end carries a connector fitting 51 adapted to be operatively associated with the fitting 46. Preferably, a pilot light 52 mounted on the panel 44 will be connected in series between the switch 49 and the cord 50.

As a result of the structure above described, the entire operating and control mechanism for a cabinet of the character herein illustrated may be readily assembled with, or removed from, said cabinet, merely by disconnecting the fitting 51, loosening the brackets 45, and withdrawing the pipe section 36 from its telescopic engagement in the header 12. Thereby, if trouble develops in the vaporizer or in any one of the controls for the cabinet, the whole assembly may be readily removed and returned to the factory for repair or replacement.

Power will be led to the assembly, of course, by an ordinary connector cord provided at one end with a connector fitting for operative association with any standard power outlet, and at its opposite end with a female plug fitting operatively associative with the male fitting 46.

I claim as my invention:

1. A vaporizer assembly comprising a tank formed to provide bottom, side, and end walls, means spanning a pair of said walls at spaced points, each of said means being provided with a tapped opening therein, a cover for said tank, said cover being formed with spaced openings registering, when said cover is in closing association with said tank, with said tapped openings, a screw enterable through each of said cover openings and taking into one of said tapped openings, each of said screws being provided with an operating knob at one end, said cover further being provided with a tapped opening therein, a further screw taking into said tapped opening in said cover and having a knob at one end, a sight glass,

means mounting said sight glass on said tank outside the same, the upper and lower ends of said sight glass being in communication with the interior of said tank at vertically spaced points, one upstanding wall of said tank being provided with an opening therethrough adjacent said bottom wall, an electrical heater including a body and a resistance heating unit, said unit being entered through said last-named opening and positioned within said tank, means clamping said body to said upstanding wall, another upstanding wall of said tank being provided with an opening therethrough at a point remote from said bottom wall, and a short pipe section rigidly fixed to said last-named upstanding wall and registering with said last-named opening for communication with the interior of said tank.

2. The combination with the vaporizer of claim 1, of a control panel including an electric switch mounted on said panel, wiring connecting said switch to control current flow to said electrical heater, a male knife-type connector fitting mounted on said panel with its blades exposed but sunken below the surface of said panel, and a power line provided at one end with a connector for operative association with any standard power outlet and at its opposite end with a female plug operatively associative with said panel male fitting.

3. A control assembly for a bath cabinet provided with a vapor-distributing header opening through a wall of said cabinet and with an electrically-energizable heating device having an energizing circuit including connector terminals accessible from the outer surface of said wall, said assembly comprising a tank, means for removably mounting said tank on the outer surface of said wall, an electrical heating unit for said tank carried by said tank, a control panel, means for removably mounting said panel on said wall, a male knife-type connector fitting mounted on said panel with its blades exposed but sunken below the surface of said panel, a switch carried by said panel, wiring providing an energizing circuit for said electrical heating unit connecting said fitting with said heating unit through said switch, a second switch mounted on said panel, a flexible connector cord connected with said fitting through said second switch, and a connector fitting on said cord associative with said connector terminals for said cabinet heating device.
